RECEPTACLE FOR A PLURALITY OF
BIPOLAR CONNECTIONSClifford R. Hartranft, Philadelphia, Pa.; Bertha
Marie Hartranft, administratrix of said Cliff-
ord R. Hartranft, deceased

Application October 24, 1950, Serial No. 191,875

1 Claim. (Cl. 339—14)

1

This invention relates to electric connectors and more particularly to receptacles forming the sockets for a plurality of outlets, and it has for its main object to provide a receptacle of the above stated type which provides simultaneously outlets for three prong non-interchangeable plugs such as used for business machines and the like and outlets for the standard conventional two prong plug, said receptacle being at the same time simple and efficient and of a sturdy construction and adapted for use in connection with two conductor networks without requiring a third conductor.

The receptacle according to the invention essentially consists of three metallic members and of an insulating body, the said three members being insulated from each other by the said body, and one of said three members being a base plate forming the bottom member of the receptacle which rests on and is attached to the wall or other structure carrying the receptacle. Said base plate member carries a ground contact and the two other metallic members are arranged on both sides of said base plate, each of said laterally arranged members consisting of a side plate with lateral contact prongs carrying wing members projecting inwardly towards the longitudinal axis of the base plate, the wing members on one side being inclined at a pre-selected angle towards said longitudinal axis and the prongs forming the contact sockets on said members being arranged near the ground contact on the base plate. The wing members on the other side of the base plate also form an inwardly projecting strip at right angles to the longitudinal axis and to the side plate and the contact prongs of the two members on both sides of the base plate form the socket members for a standard outlet adapted to be used in connection with the conventional plug.

The ground contact arranged on the base plate together with the two adjacent contacts of the two side members form a standard polarized outlet of the non-interchangeable type while the other contacts, as aforesaid, form a conventional standard outlet. Two types of connections can thus be made on the same receptacle.

Each of the bus connectors or cables of the network with which the receptacles are associated may be connected with one of the two side plates, no third conductor being necessary in this case for the ground contact on account of the direct grounding of the base plate which furnishes the ground potential for the ground contact of the polarized outlet.

2

The receptacle, notwithstanding its simple construction, is therefore adapted for a connection with two types of plugs, one being of the non-interchangeable type and the other being of the conventional two prong type.

The specific objects of the invention will be apparent from the following detailed specification.

The invention is illustrated in the accompanying drawings showing one modification thereof. It will however be understood that the modification illustrated in the drawing is shown by way of example only in order to explain the principle of the invention and the best mode of applying said principle. The specification and the drawings do not provide a survey of the various modifications by means of which the invention may be carried into effect and a departure or modification of the example which has been illustrated is therefore not necessarily a departure from the principle of the invention.

In the drawings:

Figure 1 is an elevational front view of the receptacle according to the invention when covered with a cover plate and mounted in the wall.

Figure 2 is a plan view of the receptacle.

Figure 3 is an elevational side view of the receptacle, parts of the insulating body being shown as broken away.

Figure 4 is a sectional plan view of the receptacle according to the invention, the section being taken along line 4—4 of Figure 3.

Figure 5 is a perspective view of the metallic parts of the receptacle, the insulating body being removed while the metallic parts are shown in the position in which they are held.

The connector according to the invention comprises essentially the three metallic members 10, 18, 38, embedded in an insulating body 60.

Of the metallic members the central member is a base plate or bridge support 10 which is provided with upstanding end portions 11 and 12 which carry flanges 13 and 14, each provided with a hole or holes for mounting the receptacle at the desired place by means of screws. A hole 15 is provided in the base plate for a purpose which will be explained below.

On both sides of the base plate or bridge member 10 contact carrying assemblies 18, 38 are arranged. Each contact carrying assembly includes a side plate 23 provided with ears 21, 22 each having a threaded opening or eye 24, 25 respectively, into which threaded binding posts 26, 27 respectively, may be inserted.

The contact carrying assemblies 18 and 38 are practically of identical construction. Taking the assembly 18 as an example it will be seen that this assembly comprises a side plate 23 which is provided with inwardly projecting wing members 19, 20. The wing member 19 is arranged at an acute angle with respect to the longitudinal axis of the base plate and at its end the said wing member carries two parallel upstanding prongs 31, 32 which form one of the socket contacts 28. The second wing member 20 is arranged at right angles with respect to the side plate 23 and is of U-shape carrying three contact prongs 33, 34, 35 projecting upwardly from the middle of the legs of the U-shaped strip and from the bridge piece joining the legs respectively. The two contacts 34 and 35 in this case may consist of bent strips which have base portions running towards each other until the proper distance for the upstanding parallel prongs is reached.

The contact assembly 38 is similarly provided with a side plate 43 carrying contacts 48 and 50, the former being a two pronged contact while the latter is a three pronged contact, the construction being identical with the construction of the contact carrying assembly 18.

The base plate or bridge support 10 itself carries a further contact 52, projecting from the base plate on that side on which the two pronged contacts are arranged at a proper distance from said contacts. The prongs of the contact 52 are substantially parallel to the median plane of symmetry of the base plate 10 while it will be noted that the two pronged contacts 28 and 48 have their parallel prongs arranged at an angle towards the longitudinal axis of the base plate, this angle corresponding to the angle at which the wing members 19 are arranged. The purpose of this arrangement will be explained below.

The two three pronged contacts 30 and 50 are aligned along a transverse axis which is at right angles to the longitudinal axis of the base plate 10. Of the three prongs two, 34 and 35 in assembly 18, are parallel to each other and to the transverse axis and the third prong, 33 in assembly 18, is arranged at right angles thereto.

The contact 52 mounted on the base plate 10 may be held by a screw or rivet on base plate 10 or by an arm 54 which ends in an eye or sleeve 56 encircling a hollow cylindrical sleeve 55 arranged in the center of the base plate 10 around the axis passing through the hole 15. Through the hollow interior of the sleeve 55 a screw bolt may pass which holds the parts of the receptacle together and which also holds the cover plate and fixes the receptacle on the structure on which it is mounted.

The insulating body 60 of the receptacle comprises a top portion which is provided with the two outlet caps 62, 63, one of the said outlet caps 63 being provided with three openings 64, 65, 66 arranged at such an angle that no ordinary plug connection can be inserted and a three prong plug connection can only be inserted in one way which is well defined. The second outlet cap 62 is provided with two T-shaped slots in a well known manner with the two slots 67, 68 placed apart at such a distance that an ordinary plug with two prongs may be inserted into this receptacle outlet.

The insulating body 60 is provided with two main cavities 71, 72 for taking up the contact prongs projecting from the metallic parts and it is also provided with slots 73, 74 which accommodate the side plates 23, 43 of the contact carrying assemblies 18 and 38. The shape of the insulat-

ing body is best seen in Figures 3 and 4. The bottom portion of the insulating body is seated on the base plate 10 which holds it in the center. A central hole 61 may be provided in the insulating body 60 for accommodating the sleeve 55 and the central screw which holds all the parts of the receptacle together and also holds them on the structure on which they are fixed.

The cover plate 70, Figure 1, may be placed over the two outlet caps which project from it in a well known manner concealing the base plate completely and a screw bolt 75 holding the base plate and the insulating body may also hold the cover plate 70 and may pass through the hole 15 of the base plate 10 in order to hold the receptacle on the structure on which it is mounted. The slotted head of the screw bolt 75 may be accessible from the outside to allow removal of the receptacle and of the cover plate 70 in a single operation.

The bus bars or cables of an A. C. or D. C. network (not shown) are preferably connected with or attached to the binding posts 26, 27, 86, 87 respectively. It is assumed that the bus bars form part of a distribution system. The neutral or negative bus bar is therefore always attached to the binding posts 26, 27 while the positive or high voltage bus bar is always attached to binding posts 86 or 87. Obviously if this connection has been made correctly, the receptacle is polarized and contacts 28 are always negative while contacts 48 are positive. Likewise contact 30 is always negative while contact 50 is always positive. The contacts may be marked accordingly.

The base plate 10 which forms the bottom of the entire structure is grounded either through the wall or through a special means. This ground potential is also transmitted to the contacts 52 as the plate is in contact with the arm 54 and the sleeve 56.

The receptacle is thus polarized throughout and carries an outlet for a non-interchangeable three pronged plug such as used for business machines or the like and a further outlet which is of standard construction and which may be used for any standard type of plug. Usually and in the known constructions both types of outlets are necessary and two separate receptacles are used for every business machine. Only one type of receptacle is however necessary with the receptacle according to the present invention. The supporting or base plate 10 when mounted automatically becomes grounded and therefore provides a ground potential which is necessary for the polarized or ground terminal, no special wire connection being necessary for such a purpose. The receptacle provides a combined outlet in which certain outlet sockets have a definite potential. Thus in a D. C. system the receptacle is definitely polarized when the cables or bus bars are joined to its terminals. When used in an A. C. system it will be clear that the receptacle may be used for distinguishing between the neutral conductors and phase carrying conductors. Finally the receptacle may be used like an ordinary multiple outlet for A. C.

It will be clear that while on the one hand many standardized constructions have been used the construction may be changed in many ways with changing standards or for other reasons without in any way departing from the essence of the invention as defined in the annexed claim.

Having described the invention, what is claimed as new is:

A receptacle with a grounded metallic base plate mounted on an insulating housing, hav-

ing a cover plate with two outlets arranged at a distance, one of them giving access to a normal two contact socket and the other to a three contact socket, said insulating housing consisting of an outer elongated body provided with lateral openings and an inner central block having a central bore and being provided with substantially parallel faces integral with, but partly separated from the elongated body by longitudinal slots, the inner central block being of reduced height and separated from the end portions of the other elongated bodies by cavities, a portion of one of said cavities being formed by a recess in the inner central block, comprising three metallic contact carrying members mounted on said insulating body in positions in which they are insulated from each other, two of said members being contact strips held in the aforesaid longitudinal slots and carrying contact prongs at each of their ends, said strips being bent at one end, so that the prong carrying portions are at an angle to the main portions of the strip, the contact prongs at opposite ends of one strip forming part of two different sockets, while the contact prongs at the two bent end portions at the opposite ends of different strips form contacts of the same socket, the third member including a central sleeve

member in operative connection with the grounded metallic base plate, arranged within the central bore of the inner central block and substantially at right angles to the strips and to said grounded metallic base plate, said sleeve member being provided with a prong carrying metallic strip, projecting from the center towards one socket formed by a contact group which consists of the prongs projecting from the bent end portions of the metallic contact strips, and the prongs carried by the last named strip and connected with ground, and terminal binding posts on each of said contact strips to connect the same with an electric supply line having a definite characteristic, the receptacle being thus adapted for connection with plugs of business machines having one contact prong adapted for ground connection and with normal plugs.
